By his son Lamb

UNITED STATES PATENT OFFICE.

FREDERICK HANDLEY PAGE, OF LONDON, ENGLAND, ASSIGNOR TO HANDLEY PAGE LIMITED, OF LONDON, ENGLAND.

MEANS FOR BALANCING AND REGULATING THE LIFT OF AIRCRAFT.

1,422,614.

Specification of Letters Patent.

Patented July 11, 1922.

Application filed December 6, 1921. Serial No. 520,420.

To all whom it may concern:

Be it known that I, FREDERICK HANDLEY PAGE, a subject of the King of Great Britain, residing at London, England, have invented certain new and useful Improvements in Means for Balancing and Regulating the Lift of Aircraft, of which the following is a specification.

In order to vary the relative lift of the wings on the port and starboard sides of an aeroplane flying machine to maintain the lateral stability of the said machine about the axis of flight, or to cause the lift of both wings on opposite sides of said machine to be increased, flaps or ailerons, hereafter termed flaps, are usually provided, being hinged adjacent their forward edges to the rear edges of the wings, and which flaps can be increased in angle or turned downwards as required by means operable by the pilot and which means are so well known as not to call for description in this specification, and the object of the present invention is to provide means, as hereafter described and claimed, by which the effect produced by such hinged flaps is greatly increased.

I have ascertained, as the result of numerous experiments, that by the wing having a slot or slots through the wing structure from the under surface to the upper surface and extending in length transversely to the line of flight, the lift of such a wing can be increased by admitting air from the under side to the upper side of the wing surface by way of said slot or slots, and when the wing is flown at large angles of incidence the lifting effect is considerably increased. As a further result of experiments I have found that the openings of the slots on the under surface of the wing structure should preferably be larger and more forwardly located than the openings on the upper surface.

Now the present invention consists in utilizing and adapting the above mentioned method of increasing the lift, to augment the lifting effect produced by wing flaps when the latter are increased in angle or receive a downward movement about their hinges.

According to the present invention each flap is carried by a pivot pin or equivalent hinge member, supported from the rear part of the wing, said pivot pin being so located

relatively to said flap and said wing, that when said flap is increased in angle by being given a downward movement about its hinges, the forward edge or nose of said hinged flap is distanced from the rear edge 60 of the wing, whereby a slot is automatically opened between the rear edge of said wing and the forward edge of said flap, said slot extending transversely of the line of flight and permitting of the passage of air from 65 the under surface to the upper surface of said wing structure adjacent the forward edge of said flap while when said flap is in its normal position or turned upwards said slot is closed.

The invention will be further described with reference to the accompanying drawings which sufficiently illustrate the rear portion of a wing with a hinged flap co-acting therewith, Figs. 1 and 2 showing respectively the flap in its normal position and the flap turned upwards, while Fig. 3 shows the flap turned downwards, so having the effect of automatically opening the slot between the forward edge of the flap and 80 the rear edge of the wing.

Referring to the drawings, 1 represents the rear portion of an aeroplane wing, 2 representing the rear spar of the wing. The wing flap 3 is hinged or pivoted by means 85 of brackets 3^x extending below and engaging a pivot 4, (or hinge member of any suitable construction), carried by brackets 5, extending rearwards and downwards from the rear spar 2 of the wing 1. The 90 wing structure 1 in front of the forward edge of the flap 3 extends somewhat rearwardly of the wing spar 2.

It will be observed that when the flap 3 is in its normal position, namely continuous 95 in its direction with the after part of the wing as at Fig. 1, or is turned upward as at Fig. 2, the slot 6, between the forward edge of the flap and the rear portion of the wing, is closed, while when the flap 3 100 is turned downwards as at Fig. 3 upon its pivot 4, the slot 6 is open and permits air to pass from the under surface of the wing to the upper surface above the flap 3.

Since I have found that the opening of 105 the slot 6 should, on the under surface be preferably larger and more forwardly located than the opening on the upper surface, the extension 1^x of the wing 1, rearward of the spar 2 and opposed to the for- 110

ward edge or nose of the flap 3, is curved rearwardly, that is, is concavely curved at 7, from the lower surface at about a point 8, to the upper surface at a more rearward 5 point 9, so that when the flap 3 is turned downwards as at Fig. 3, the slot 6, produced between the flap 3 and the rear part of the wing, is larger on the lower surface than the opening of the slot on the upper 10 surface, and moreover the opening of the slot on the lower surface is more forwardly located than the opening on the upper surface. Moreover the walls of the slot 6 formed by the rear edge of the wing and 15 the nose of the flap are curved rearwardly.

What I claim as my invention and desire to secure by Letters Patent is:—

1. In laterally balancing or regulating the lift of the wings of aeroplane flying machines; the combination with said wings, of flaps located at the rear edges of said wings, hinge members to support said flaps, and means extending from the structure of said wings to support said hinge members in such 20 position relatively to said wings and said flaps, that a slot is formed between the forward edge of each of said flaps and the rearward edges of said wings when said flaps are turned downwards about their hinges, 25 and said slot is closed when said flaps are in their normal or upturned positions.

2. In laterally balancing or regulating the lift of the wings of aeroplane flying machines; the combination with said wings, of flaps located at the rear edges of said wings, hinge members to support said flaps, means 30 extending from the structure of said wings to support said hinge members in such position relatively to said wings and said flaps, 35 that a slot is formed between the forward edge of each of said flaps and the rearward edges of said wings when said flaps are turned downwards about their hinges, and said slot is closed when said flaps are in their 40 normal or upturned positions, and constructing the rearward edges of said wings adjacent the forward edges of said flaps inclined 45 upwardly and rearwardly from the lower surface to the upper surface of said wings to 50 produce slots larger on the under surface

than on the upper surface of the structure when said flaps are turned downwards about their hinges.

3. In laterally balancing or regulating the lift of the wings of aeroplane flying machines; the combination with said wings, of flaps located at the rear edges of said wings, hinge members adjacent the lower surface and forward edge of said flaps, means to connect said hinge members to said flaps, brackets extending downwardly and rearwardly from the rear spars of said wings to support said hinge members in such position relatively to said wings and said flaps that a slot is formed between the forward edge of 55 each of said flaps and the rearward edges of said wings when said flaps are turned downwards about their hinges and said slot is closed when said flaps are in their normal or upturned positions. 70

4. In laterally balancing or regulating the lift of the wings of aeroplane flying machines; the combination with said wings, of flaps located at the rear edges of said wings, hinge members to support said flaps, means 75 extending from the structure of said wings to support said hinge members in such position relatively to said wings and said flaps, that a slot is formed between the forward edge of each of said flaps and the rearward 80 edges of said wings when said flaps are turned downwards about their hinges, and said slot is closed when said flaps are in their normal or upturned positions, and constructing the rearward edges of said wings 85 adjacent the forward edges of said flaps concavely curved from the lower surface to the upper surface to produce slots having openings larger on the lower surface than on the upper surface and having the walls of said 90 slot comprised by the rear edges of said wings and the forward edges of the flaps curved rearwardly from the under surface to the upper surface.

In witness whereof I have hereunto set 95 my hand in the presence of two witnesses.

FREDERICK HANDLEY PAGE.
